CLAIM

The design for a door seal assembly, as shown and described.

DESCRIPTION

FIG. 1 is a perspective view from above, to the front and to one side of a door seal assembly including a mounting bracket with an insert installed in the mounting bracket; FIG. 2 is a perspective view from above, to the front and to one side thereof showing the insert removed from the mounting bracket;

FIG. 3 is a front view thereof;

FIG. 4 is a top view thereof;

FIG. 5 is a left side view thereof;

FIG. 6 is a bottom view thereof; and,

FIG. 7 is a right side view thereof.

In the drawings, the broken dash-dash-dash lines depict environmental subject matter only and form no part of the claimed design, and the broken dot-dash-dot lines depict the bounds of the Claim. The drawings contain a symbolic break. The area between the break lines forms no part of the claimed design.
